TRAILER ROOFTOP AIR-CONDITIONER COVER

Benjamin C. Baugh and Don Bruce Cleveland, Wichita,
Kans., assignors to The Coleman Company, Inc.,
Wichita, Kans., a corporation of Kansas

Filed Mar. 14, 1968, Ser. No. 10,972

Term of patent 14 years

U.S. Cl. D23—142
Int. Cl. D23—04

FIG. 1

FIG. 2

FIG. 3

FIG. 4

FIG. 5

FIG. 1 is a side elevational view of the rooftop air-conditioner embodying our new design;

FIG. 2 is an enlarged side elevational view, both sides having an identical appearance in elevation;

FIG. 3 is a front elevational view;

FIG. 4 is a rear elevational view; and

FIG. 5 is a top plan view.

The trailer in broken lines in FIG. 1 is shown for illustrative purposes only. The dominant features of the air-conditioner cover are shown in full lines.

We claim:

The ornamental design for a trailer rooftop air-conditioner cover, as shown and described.
